DESIGN FOR A GOLF CLUB HEAD PROTECTOR

Maxwell M. Booxbaum, Mount Vernon, N. Y.

Application November 12, 1946, Serial No. 134,689

Term of patent 3½ years

(Cl. D34—5)

To all whom it may concern:

Be it known that I, Maxwell M. Booxbaum, a citizen of the United States and a resident of Mount Vernon, county of Westchester, and State of New York, have invented a new, original, and ornamental Design for Golf Club Head Protector, of which the following is a specification, reference being had to the accompanying drawings, forming part thereof, and in which

Fig. 1 is a front elevational view of a golf club head protector showing my new design,

Fig. 2 is a rear elevational view, and

Fig. 3 is an end view.

I claim:

The ornamental design for a golf club head protector, substantially as shown.

MAXWELL M. BOOXBAUM.
